UNITED STATES PATENT OFFICE.

CHARLES D. SEEBERGER, OF YONKERS, NEW YORK, ASSIGNOR TO OTIS ELEVATOR COMPANY, A CORPORATION OF NEW JERSEY.

CONVEYER.

1,034,841.

Specification of Letters Patent.

Patented Aug. 6, 1912.

Application filed December 12, 1906, Serial No. 347,415. Renewed January 13, 1910. Serial No. 537,931.

To all whom it may concern:

Be it known that I, CHARLES D. SEEBERGER, a citizen of the United States, residing at Yonkers, in the county of West-
5 chester and State of New York, have invented certain new and useful Improvements in Conveyers, of which the following is a specification, reference being had therein to the accompanying drawing.

10 My invention relates to conveyers, and especially to that class of conveyers wherein a traveling foot-way, preferably in the form of a series of connected steps extending between different levels, is adapted to carry
15 or transport freight or passengers.

The object of the present invention is to provide certain novel and useful features in this class or type of machines, and the invention consists in the constructions, arrangements and organizations of parts 20 hereinafter set forth and then specifically pointed out in the appended claims.

In the accompanying drawings, which illustrate embodiments of the several features of my present invention—Figure 1 is a detail view showing a general arrangement of drive, linkage and upthrust; Fig. 2 is a sectional view on the line 2—2 of Fig. 1, looking in the direction of the arrow, the 25 drive being omitted; Fig. 3 is a detail view in side elevation of the drive and linkage on an enlarged scale, showing also two-part links; Fig. 4 is an end view of the parts of Fig. 3; Fig. 5 is a sectional view through 30 an axle and its associated links; Fig. 6 is a view in side elevation showing a hand-rail and drive mechanism therefor; Fig. 7 is a detail central sectional view of the upper drive wheel of Fig. 6; Fig. 8 is a detail top view of 35 the hand-rail driving sprocket chain; Fig. 9 is a side view of a grated or comb landing at the top of the incline and one of the steps constituting the carrier or foot-way; Fig. 40 45 Fig. 10 is a top plan view of the parts of Fig. 9; Fig. 11 is a sectional view of a form of hand-rail; and Fig. 12 is a diagrammatic view showing an assemblage of the several parts illustrated in detail in the other figures.

50 The machine to which the various improvements herein disclosed may be applied, consists of a series of steps adapted to travel on suitable tracks between different levels to transport passengers or freight in either
55 direction, according to the direction of

movement of the steps. Each step comprises a rectangular frame provided with a tread and a riser, as shown for example in Fig. 9, and having a suitable wheel-base 11 adapted to receive an associated axle 12, 60 these parts being connected in any suitable manner. The wheel-base consists, as is usual, of oppositely extending arms which project beyond the sides of the step so as to provide a wheel-base of greater area than 65 the step itself, and are provided at their outer ends with wheels 13 and 14 adapted to run upon suitable tracks extending in an inclined run between the levels and at each level in a horizontal run to form a landing, 70 one of the arms being angular or offset to accommodate the wheels to the different vertical planes of the tracks. The steps are connected by means of suitable linkage, preferably in the form of racks, adapted to 75 receive and coöperate with a drive-wheel or sprocket for moving the steps. The general arrangement and disposition of the parts heretofore referred to is now well understood in the art from machines as actually 80 constructed by me and in public service, and need not, therefore, be specifically described.

Between the wheel-base and ends of the steps the axles 12 receive rack-links 15 and 16, which are pivotally held upon the axles 85 by any suitable means and coöperate with a suitable drive 17. The links 15 and 16 are in male and female form respectively, the sleeves 18 of the former receiving the axles and extending within collars 19 of the latter (Fig. 5), the several parts being provided preferably with interposed anti-friction bushings. The male links are provided with teeth extending their entire length so that the end teeth are below or in the line 90 of the axles, and the female links have teeth arranged intermediate the collars, as clearly shown in Figs. 1 and 3.

By providing the male links with teeth under the axles, and omitting the teeth of the female links below the axles or collars, I am enabled to provide a much stronger construction in that the male links have more metal in the line of the axles than the female links by reason of the fact that the latter 100 are bored out to receive the sleeves of the former. As the bore in the male link is merely large enough to receive the axle, and the bore in the female link is larger in order to receive the sleeve of the male link, it is 110

apparent that there is more metal on the male link at the root of the end teeth in the line of the axle than there would be if such teeth were on the female link. This of course reduces the liability of breakage and provides a much stronger construction. Moreover, as the collar of the female link surrounds the sleeve of the male link it will hold the latter in place in the event of any fracture therein.

In linkage as heretofore constructed the body of each link and its teeth are formed in an integral piece. Of course in such construction it is necessary to bodily remove a link in the event any of its teeth break or become worn by use, and the removal and replacement of an entire link is an inconvenient operation and consumes much time. Furthermore, the integral construction referred to is necessarily very expensive for the reason that as the teeth must be extremely hard and durable to resist the heavy wear, it is necessary to make the entire link of expensive material such as steel, etc. In the present form I utilize a built-up link in which the body is adapted to be connected with the associated parts and carries removable teeth. The teeth may of course be connected to the body in any suitable way, but I prefer to make all of the teeth for each link in a separate integral structure adapted to be fastened to the body, and for this purpose I form the teeth integral with a base or strip 20 adapted to be secured to the body by suitable means such as the lag screws 21. By this construction the body of the link may be made of comparatively cheap material, such as cast metal, while the teeth themselves may be made of hardened, durable material to resist the wear, and moreover when it is necessary for any reason to renew or replace any of the teeth this operation may be readily and easily accomplished by merely manipulating the retaining screws and without disconnecting the line of connected sections or steps.

In linkage as heretofore constructed the sides of the teeth have been inclined, and the engagement of the sprockets therewith has of course produced a thrust tending to raise or lift the links and their connected steps proportional to the inclination of the teeth. I obviate this difficulty by providing the links with straight teeth, or teeth having straight sides, so that the face of the teeth is at right angles to the direction of travel of the linkage, whereby the upward thrust is eliminated as the force or stress of the drive is then in the line of the links, or parallel with the plane passing through the axis of the drive at a right angle to the line of the links. This form of tooth may of course be employed where the links are at the ends of the axles or where they are at an intermediate point under or below the steps. Figs. 3

and 4 illustrate this feature upon an enlarged scale, showing the straight sides or faces of the teeth of the racks or linkage, from which it will be apparent that the upward thrust is eliminated and the force or stress of the drive is delivered to the links in a line parallel with the axis of the drive which is at right angles to the normal line or plane of the links.

The form of tooth just described may of course be employed with any suitable drive delivering its force or thrust in the line of the links, and for this purpose I provide teeth upon the sprockets 17 which are curved toward their ends. By reference to Fig. 3 it will be seen that the contact of the sprocket and links is at all times at a point in the line of the links.

The action of the driving sprocket on the end teeth of the links causes these links to tend to turn on their axis, and in order to overcome this action I provide a suitable upthrust, which may be of any desired form, that shown consisting of a bracket 22 secured to the frame and having suitable anti-friction rollers 23 journaled along its lower edge. The rollers as shown are situated in the vertical plane of the female links, which in the embodiment here shown are provided with continuous upper webs or faces 24 adapted to contact against the rollers. By this construction the upthrust device engages alternate links. As the upthrust is longer than any single link the tendency of one of the male links to turn on its axle when the drive engages the end tooth beneath that axle is resisted by the female link at the opposite end contacting with the upthrust. It is of course obvious that the contact surface on the back of the links may be on either the male or the female links. The maximum tendency to turn on the axis is of course on the male links, on account of the end teeth being under the axles, although the female links likewise have the same tendency, and it is obvious that the upthrust may be arranged to coöperate with either or both sets of links.

In Figs. 6 and 7 I have shown a construction in which I utilize two drive wheels for the hand-rail in place of the single large wheel now commonly used. In many installations it is not feasible to employ a large drive wheel at the end of the run, and where a small drive wheel is employed it has been found unsatisfactory by reason of the fact that the small wheel gave such a small arc of contact for the hand-rail that the latter was not properly driven. These hand-rails are heavy, being usually made of strips of canvas cemented or otherwise secured together, and depend for their motion upon their friction with the drive wheel; it is obvious that when a small drive wheel is used the area of contact between the rail

and wheel is so reduced that the rail, being a heavy structure, is not properly driven. To obviate this defect I provide a pair of wheels 25 and 26, which are placed one above the other and are connected by a chain or other suitable band 27 with which the inner face of the hand-rail contacts so that the frictional area between the hand-rail and the drive is greatly increased. In the form 10 shown the wheels are in the form of sprocket wheels and the band is in the form of a sprocket chain, although of course the form of these parts may be varied. The sprocket chain is provided with bridge pieces 28 as 15 shown in Fig. 8 extending transversely from one side of the chain to the other and adapted when the parts are operated to contact with the inner face of the hand-rail 32 as clearly shown in Fig. 7. The wheels are 20 preferably built up as shown in Fig. 7 in which a central casting 29 is mounted on a drive shaft 30 and is provided with teeth in its periphery for the chain, and the shrouds 31 are bolted to the casting as shown in Fig. 25 7. The shrouds are of sufficient size to project into alignment with the tops of the bridge pieces so as to engage the inner face 30 of the hand-rail 32, which is of the usual form having inturned sides or edges as shown in Fig. 7. Its inner face frictionally 35 engages with the shrouds of the drive wheels and with the bridge pieces of the chain so that the area of contact between the hand-rail and the drive is increased to provide sufficient frictional engagement to positively drive the rail without slipping.

The hand-rail is composed of strips of canvas bent back and forth upon each other and preferably connected by rubber, cement, 40 or other suitable material. In cross section the layers or plies of canvas are as represented in Fig. 11, where it will be seen that starting with the edge 33 on the inside the canvas is folded back and forth in successive 45 superposed layers and that the last layer is then carried up around the edges of the intermediate layers as shown at 34 and extended across the width of the inner face where it is again brought down as at 35 to 50 inclose the opposite edges of the layers. The tops of the parts 34 and 35 are straight as at 36 to provide bearing surfaces to contact with the guide.

In Figs. 9 and 10 I have shown a comb or 55 grated landing and a corresponding form of step. The landing or floor 37 is provided with a series of forwardly projecting strips 38 suitably spaced apart, beveled or inclined upon their lower faces at their free ends, as 60 indicated at 39. The treads of the steps are grated, as clearly shown in Fig. 10, by means of alternately raised and depressed portions 40 and 41, respectively. The depressed portions of the gratings of the treads of the 65 steps do not cut through the risers but are

inclined upwardly at the front edges of the steps as indicated at 42 and merge into the plane of the parts 40 at the front edge of the steps in proximity to the risers. By this construction the risers are unbroken and 70 provide continuous service uniformly over their exposed areas.

The tracks upon which the supporting wheels 13 and 14 of the steps run are in the usual form upon the incline and landings where they extend side by side, it being understood that the front and rear wheels are in different vertical planes, and the horizontal portions 43 of the tracks at the upper landing are curved as at 44 to provide a 80 drop for the step, so that just before the inclined portions 39 and 42 of the comb landing and grated steps, respectively, come into contact the step will drop away below the level of the comb. By this arrangement each succeeding step engages the comb at the instant the preceding step passes below it.

Having described my invention what I claim as new and desire to secure by Letters 90 Patent of the United States, is—

1. In a device of the class described, linkage comprising male and female links having teeth with a flat face, the teeth on the former extending to the ends thereof, and 95 the teeth on the latter being intermediate the ends, and means to drive the links.

2. In a device of the class described, a series of steps having axles, links having sleeves connecting alternate axles, teeth having a flat face on the links extending to the ends thereof, links having collars for the sleeves of said first named links, teeth having a flat face on the last named links intermediate their ends, and means to engage the 105 teeth to drive the links.

3. In a device of the class described, a series of movable steps, links connecting the steps and having teeth with straight sides, and a drive having curved teeth. 110

4. In a device of the class described, a series of movable steps, links connecting the steps and having teeth each with a flat face, and a drive having curved teeth engaging the flat faces of the link-teeth. 115

5. In a device of the class described, a series of movable steps, links connecting the steps, alternate links having upper webs or faces, a drive for the links, and an up-thrust for the webs over the drive. 120

6. In a device of the class described, a series of movable steps, links connecting the steps, removable teeth on the links, and a drive engaging the teeth.

7. In a device of the class described, a 125 series of movable steps, links connecting the steps and consisting of body portions and separable teeth, and a drive engaging the teeth.

8. In a device of the class described, a 130

- series of movable steps, links consisting of body portions connecting the steps and detachable strips carrying teeth, and a drive engaging the teeth.
5. 9. In a device of the class described, a movable hand-rail, and an end drive therefor consisting of a pair of wheels and a connecting band engaging with the inner face of the rail.
10. 10. In a device of the class described, a movable hand-rail, and an end drive therefor consisting of a pair of sprocket wheels engaging with the inner face of the rail and a sprocket chain on the wheels.
15. 11. In a device of the class described, a hand-rail, and a drive therefor at the terminal consisting of a driven sprocket chain frictionally engaging the inner face of the rail.
20. 12. In a device of the class described, a hand-rail, and driving mechanism at a terminal consisting of a sprocket-chain frictionally contacting with the inner face of the rail.
25. 13. In a device of the class described, a hand-rail, and driving mechanism at a terminal consisting of a sprocket-chain having cross-pieces frictionally contacting with the rail.
14. In a device of the class described, a series of movable steps having grated treads, the gratings terminating short of the risers, and a comb-landing co-operating with successive treads.
15. In a device of the class described, a series of movable steps each having a solid riser and a grated tread, and a comb-landing entering the gratings of successive treads as far as the riser.
16. In a device of the class described, a series of movable steps each having a solid riser and a grated tread, tracks on which the steps run and provided with depressions, and a comb-landing arranged above the depressions and adapted to receive the gratings of the steps to the risers.
17. A step for moving stairways having a riser and a grated tread, the gratings of the tread terminating in front of the riser.
18. A step for moving stairways having a continuous or unbroken riser and a grated tread.

In testimony whereof I affix my signature in presence of two witnesses.

CHARLES D. SEEBERGER.
